UNITED STATES PATENT OFFICE.

LEWIS HALLOCK NASH, OF BROOKLYN, ASSIGNOR TO THE NATIONAL METER COMPANY, OF NEW YORK, N. Y.

GAS-ENGINE.

SPECIFICATION forming part of Letters Patent No. 334,039, dated January 12, 1886.

Application filed August 20, 1885. Serial No. 174,893. (No model.)

To all whom it may concern:

Be it known that I, LEWIS HALLOCK NASH, a citizen of the United States, residing at Brooklyn, in the county of Kings and State 5 of New York, have invented new and useful Improvements in Gas-Engines, of which the following is a specification.

My invention is directed to the production of a double-acting gas-engine of single-acting 10 cylinders placed in line in which the gaseous mixture is ignited at each end of every stroke, whereby a double-ended plunger may be used to receive the impulses of the explosions in both cylinders at both the forward and backward movements of the double-ended plunger. 15

The objects of my improvements are to ignite the charge in a highly-heated combustion-chamber, and at the same time provide for a comparatively cool condition of the wearing-20 surfaces of the plunger and the valve, so as to be lubricated in the ordinary manner, to provide very compact operating connections for a double-ended plunger operated in a right line, and driving a connection moving in a 25 curvilinear line, by the combined action of two single-acting cylinders, whereby to obtain a rotary or a rectilinear movement, or both, from the movement of the double-ended plunger, to operate a crank-shaft and an air-30 compression piston, working parallel with the double-ended plunger.

Referring to the accompanying drawings, Figure 1 represents a vertical longitudinal section of a double-acting gas-engine of single-35 acting cylinders, embracing my improvements; Fig. 2, an elevation of the same, showing one supply and a mixing valve for the combustible fuel in section. Fig. 3 shows in section the connection of the supply-valve case 40 with the combustion-chamber. Fig. 4 represents a horizontal section of what I call the "mixing-valve" of the compression-cylinder, showing the inlet-passages for the gas and air, and the valve-connection with the compres-45 sion-chamber.

The engine-frame A supports separate and distinct single-acting trunk-cylinders placed in the same horizontal line, within which operates a double-ended plunger, B' B², prefera-50 bly cast in one piece, which has an opening, B³, in the middle of its length, to receive the

operating connection between the cylinders. The bearing-cylinders A' A² for the double-ended plunger are comparatively short and are provided with suitable packing-rings for 55 maintaining a joint for the plunger, and constructed with a jacket, W, for the circulation of water for lowering the temperature of its wearing-surfaces. The combustion-chambers C' C² for each cylinder are formed by separate cylindrical caps or extensions D' D², the inner walls of which do not touch the plunger-trunks, and they may be externally covered with a non-conducting covering, D³, and it is by this construction that I obtain a hot combustion-chamber with a comparatively cool bearing-cylinder. The engine-valve cases J are mounted directly upon the hot combustion-chamber caps D' D² and are provided each with cooling jackets W', which do not 60 modify the temperature of the combustion-chambers. The water-jackets of the cylinders and of the valves may connect for a continuous flow, or they may have separate supply and discharge pipes. The valve-case is 65 bolted to the combustion-chamber, so that very little heat from the latter will be communicated to the former, and a small cooling-jacket will be sufficient for the valve-case. A compression-cylinder, H', is placed in the 70 frame, preferably beneath one of the power-cylinders, for compressing the charge for the engine. It is provided with a suitable air and gas inlet valve—such as that shown at L in Fig. 2—and a suitable discharge-valve—such as 75 that shown at h in Fig. 1—by which the compressed products are discharged from the compressor into a reservoir, A³, by the pipe-connections A⁴, from whence the charges are conveyed by the pipes A⁵ to the supply-valves 80 placed at J. The reservoir A³ is formed in the base of the frame, preferably beneath the compressor. The power-transmitting shaft I' is mounted in the frame beneath the other cylinder, and the connections of this shaft, 85 the air-compressor piston, and the plunger I will now describe. These three things are connected to a rocker-arm, G, which is pivoted at g to the foot of the frame, and, rising from said pivot, passes at its upper end into 90 the opening B³ in the double-ended hollow plunger, to which it is connected by means of 95 100

separate and distinct plunger-rods between the bearing-cylinders of the plungers, so as to drive the rocker-arm back and forth with the movement of the pistons. Between the 5 pivot of the rocker-arm and its connection with the double-ended plunger, the crank-shaft and the air-compressor piston are connected to the rocker-arm by connecting-rods *a b*, standing in opposite directions, so that the 10 back and forth movements of the rocker-arm *G* will drive the piston *H* of the air-compressor on one side of the rocker-arm and drive the crank-shaft *I'* on its opposite side. This places the rocker-arm between the power-cylinder, 15 the air-compressor, and the crank-shaft in a compact arrangement to utilize the rectilinear movement of the double ended plunger.

As the rocker-arm describes the arc of a circle struck from its pivot, it is necessary to 20 provide connections with the double-ended plunger to accommodate such movement with the least amount of friction, and for this purpose I prefer to use connecting-rods *a* and *b* with rolling or rocking bearings *c c*, and provide for taking up the wear of such bearings 25 by making one of the latter adjustable in the head of the rocker-arm by means of a key, *d*, or other suitable means. The double-ended plunger is a single hollow cylinder provided 30 at each end with a suitable piston-head, *e*, and has an opening or slot, *B*³, in the middle of its length to receive the rocker-arm and permit its connection and adjustment with the plunger connecting-rods. These rocker-bearing 35 connections, which I prefer to use, require no lubrication, and reduce the friction of the piston-rod joints to a minimum. These separate and independent connecting-rods operate in the same plane, and by having abutting bearings 40 upon the plunger-heads and upon the rocker-arm they act as a single connecting-rod to transmit the power of the double-plunger 45 to the rocker-arm, to drive its non-pivoted end back and forth, and through its connecting-rod *D* drive the crank-shaft *I'* to transmit the power, and by the connecting-rod *E* operate the air-compressor piston *H* to compress the charge for the engine.

By providing comparatively small bearing-cylinders for the double-ended trunk-plunger 50 I am enabled to use comparatively long caps to form separate chambers for the combustion of the charge. These short cylinders are provided at their open ends with bearing-rings *f*, 55 for taking up the wear of the trunk-plunger, while the inner end of the cylinder has packing-rings *f*² at its junction with the cap for forming tight joint. The plunger works through a comparatively cool bearing-cylinder into a 60 hot combustion-chamber formed by the separate cap, the inner walls of which have a clearance-space, *h*, around the plunger, so that it has no contact with the combustion-chamber proper. This construction permits the combustion-chamber to become very hot, in order 65 that the gases may lose no heat while doing their work, while the bearing part of the plun-

ger will work in a comparatively cool cylinder. I prefer to place the valve-case *J* at the end of the cylinder-cap and provide it with a 70 cooling-jacket, as stated. The provision of a short bearing-cylinder for the plunger, having a cooling-jacket independent of the cap forming the combustion-chamber, having no cooling-jacket and no contact with the plunger, and 75 a valve-chamber having a cooling-jacket, gives the advantage of a hot chamber for the combustion of the charge and comparatively cool 80 wearing-surfaces for the rubbing parts, so as to be lubricated, whereby the gases are burned in a very hot combustion-chamber, and little heat is abstracted by the walls of the cylinder, and a great saving in power is thereby obtained. The supply-valves for the combustion-chambers are operated by the connecting-rods *f*³ and controlled by a governor device carried by the balance-wheel, and the mixing-valve for the compression-cylinder is operated and controlled by the connecting-rod *l* and cam *l'*; but as these matters do not form 90 part of my present invention a particular description of these parts is therefore deemed unnecessary. The air-compression cylinder is also provided with a cooling-jacket, *W*², which may be continuous with the cylinder-jacket, as 95 shown. The reservoir *A*³ is for the storage of a uniform mixture of gas and air, and it is from this reservoir that the power-cylinders are directly supplied by the valves through the pipe-connections *A*⁴ and *A*⁵. (Shown in 100 Fig. 2.)

In Fig. 4 the mixing-valve connection with the compressor is shown by the passage *i* in the cylinder-head, while the air-passage is shown at *j*, and passage for the gas is shown 105 at *k*, so that as the valve *L* is reciprocated a certain portion of air will be sucked into the cylinder and a certain portion of gas will also pass therein.

An important advantage in my double-acting gas-engine is in combining two open-ended cylinders with a single double-ended plunger, so as to avoid the necessity for stuffing-boxes for either cylinder and maintain cool piston-connections, as contradistinguished from a 110 double-acting gas-engine having a piston-rod extending through one of the combustion-chambers, which is exposed to the intense heat of the gas and must work in stuffing-boxes. 115

I have shown and described a short bearing-cylinder for the plunger-trunk and a comparatively long cap forming combustion-chamber and joint-forming rings secured in the short cylinder, and it is by this construction that I 120 obtain the advantage of a long hot combustion and a short bearing cylinder, greatly lessening the weight and expense of the engine, and also the advantage of avoiding the expense of forming a perfectly-true cylinder, since the 125 packing-rings form the joint upon the plunger-trunk.

The specific construction of bearing-pin connecting-rods and connecting-rods for pistons

having rolling or rocking bearings is not claimed herein, as such devices are made the subject of separate and distinct applications for patents made by me.

5 I have stated the advantages of a short comparatively cool bearing-cylinder having a separate cap forming combustion-chamber having a greater interior diameter than the bearing-cylinder, and joint-forming rings in the said 10 short cylinder, and it will be seen that such construction gives a bearing-cylinder much shorter than the stroke of the engine, and that a long plunger works within a long combustion-chamber which is maintained at a high 15 heat.

I claim--

1. The combination, in a gas-engine, of a double-ended plunger with bearing-cylinders therefor placed in line, having cooling jackets 20 and separate combustion-chambers formed of non-jacketed cylinder-caps having their inner walls free of contact with the plunger-trunks, and suitable operating connections for the double-ended plunger and power-transmitting 25 crank, substantially for the purpose specified.

2. The combination, in a gas-engine, of a double-acting piston or plunger with a combustion-cylinder chamber for each end of said plunger, and a pivoted rocker-arm having 30 suitable connections with the said plunger between the open ends of said cylinder-chambers, and suitable connections with the crank-shaft between the plunger and pivot of said rocker-arm, substantially as described, for the purpose 35 specified.

3. The combination, in a gas engine, of a bearing-cylinder having a water-cooling jacket and a combustion-chamber formed thereon by a separate cap, with an induction-valve case 40 having a water-jacket mounted upon the hot combustion-chamber, whereby the bearing-cylinder and the supply-valve are prevented from being unduly heated while the combustion-chamber is maintained highly heated, 45 substantially as described, for the purpose specified.

4. In combination, in a gas-engine, a bearing-cylinder, a plunger, a separate cap forming combustion-chamber, and joint-forming 50 rings having a bearing upon said plunger, the said cylinder having a length less than the stroke of the engine, the said cap forming combustion-chamber having an interior diameter greater than that of the plunger, to allow the 55 latter to operate therein, and maintained at a greater heat than said cylinder, substantially as described, for the purpose specified.

5. The combination of the bearing-cylinders placed in line and separate cap forming combustion-chambers, with a double-end plunger, the separate plunger connecting-rods *a b*, and an air-compression cylinder arranged parallel 60 with the bearing-cylinder, with a pivoted rocker-arm, *G*, connecting said plunger between the open ends of said cylinders, the crank-shaft connecting-rod *D*, and compressor connecting-rod *E*, whereby the combined power 65

of the cylinders is transmitted in a rotary motion for the crank-shaft and a reciprocating motion for the compressor, substantially as 70 described.

6. The combination of the power-trunk-cylinders arranged in line, the double-ended plunger, and the rocker-arm, with the connecting-rods *D* and *E*, the compression-cylinder, the storage-chamber, the engine supply-valves, and the supply-connections for the charge for both cylinders, substantially as 75 described.

7. A gas-engine composed of two power-cylinders placed in line, each having a combustion-chamber, and a rigid double-ended piston or plunger having power-transmitting connections adapted to rock upon contact-bearings upon each piston-head and upon the 85 said power-connections, substantially as described.

8. The combination, in a gas-engine, of two power-cylinders placed in line, and a piston or plunger for each cylinder rigidly connected, 90 having power-transmitting connections adapted to rock upon contact-bearings at their points of connection, and a compression-pump connected with said piston-rocking connections, substantially as described, for the purpose 95 specified.

9. The combination, in a gas-engine, of a double-ended plunger, with bearing-cylinders therefor placed in line, and separate combustion-chambers formed of cylinder-caps having 100 their inner walls free of contact with the plunger-trunks, and suitable operating-connections for the double-ended plunger and power-transmitting crank, substantially as described, for the purpose specified. 105

10. The combination, in a gas-engine, of two power-cylinders placed in line, and jointed connected pistons or plungers for each cylinder, with an independent cylinder and piston arranged below one of said power-cylinders, a 110 power-transmitting shaft arranged below the other power-cylinder, and suitable connections for the moving parts, substantially as described.

11. The combination, in a gas-engine, of two short bearing-cylinders arranged in line, with a piston or plunger for each cylinder, having a stroke greater than the length of said cylinder, a combustion-chamber forming cap for each cylinder, and suitable operating-connections 120 for said plungers, substantially as described, for the purpose specified.

12. The combination, in a gas-engine, of two power-cylinders placed in line, and connected pistons or plungers for each cylinder, with a 125 storage-supply-chamber, and suitable supply-connections for the charge for both cylinders, substantially as described.

13. The combination, with the power-cylinders, each having a combustion-chamber placed 130 in line and a separate piston for each cylinder, of a connecting-rod device for said pistons, consisting of separate and independent connecting-rods, and a vibratable or rocking arm

having bearing-surfaces for the abutting ends of said connecting-rods, substantially as described, for the purpose specified.

14. The combination, with the power-cylinders placed in line and a piston for each cylinder, of a rocking or vibratable arm having bearing-seats on opposite sides, and independent connecting-rods having rolling or rocking contact-seats upon the vibratable arm and upon the pistons, substantially as described, for the purpose specified.

15. The combination, with the power-cylinders placed in line and a piston for each cylinder rigidly connected, of a pivoted arm having its non-pivoted end entering an open way in said rigid piston connection at or about the middle of its length, provided with curved bearings on opposite sides, and independent con-

necting-rods having abutting end bearings upon the moving parts, substantially as described, for the purpose specified.

16. The combination, with two power-cylinders, each having a combustion-chamber placed in line and rigidly-connected pistons for each cylinder, of a pivoted arm having a fixed and an adjustable bearing, the independent rods connecting the pivoted arm, and an adjusting device for said rocker-arm bearing, substantially as described, for the purpose specified.

In testimony whereof I have hereunto set my hand in the presence of two subscribing witnesses.

LEWIS HALLOCK NASH.
